WARP DRAWING MACHINE

Russell P. Drake, Caledonia, Ill., assignor to
 Barber-Colman Company, Rockford, Ill., a corporation of Illinois

Application June 27, 1946, Serial No. 679,822

16 Claims. (Cl. 28—44)

1

The invention pertains to machines for drawing in warps and has particular reference to a mechanism for controlling the positions of heddle frames of the type having heddles freely slideable endwise of the frame, so as to shift the frames endwise with respect to the reed and parallel thereto whereby to permit the drawing in of a full harness.

Heddle frames of the character set forth are commonly equipped with backers to hold the heddles in compacted relation for release by the release keys. Such frames correspond in width to the width of the reed and when the full width of the frames is to be drawn in, the backers although occupying fully retracted positions in the heddle frames interfere with and prevent the operation of the drawing-in needle. The backers are usually made of substantial thickness and it has heretofore been the practice when drawing in the full width of the heddle frames to shift the same manually with respect to the reed so as to avoid interference by the backers and allow the last remaining heddles in the harness to be released for threading. Such manual shifting of the frames has been found objectionable not only from the standpoint of the time consumed but because it results in an uneven distribution of the heddles along each frame since a sudden shifting of the frame leaves a space between the previously released heddles and those finally released after the manual shifting operation, with the result that the heddles are not properly aligned in the harness when the latter is placed in the loom.

The primary object of the present invention is to effect a shifting of the heddle frames progressively during the drawing in operation to the end that a full harness can be drawn in automatically without the intervention of the operator, and at the same time effect an even distribution of the heddles across the full length of the harness.

A further object is to provide a heddle control or shifting mechanism of practical character for imparting a progressive shifting movement to the heddle frames.

The objects of the invention thus generally set forth, together with other and ancillary advantages, are attained by the construction and arrangement shown by way of illustration in the accompanying drawings, in which:

Figure 1 is a fragmentary side elevational view, somewhat schematic in character, of a warp drawing machine embodying my invention.

Fig. 2 is an enlarged view in front elevation and

2

illustrating the shifting mechanism of the invention.

Fig. 3 is a fragmentary transverse sectional view taken approximately in the plane of line 3—3 of Fig. 2.

Fig. 4 is a fragmentary perspective view somewhat schematic in character and showing the heddle shifting mechanism from the side of the machine opposite that shown in Fig. 1.

Fig. 5 is a schematic view showing the relation of one of the heddle frames with respect to the reed at the beginning of the drawing in operation.

Fig. 6 is a similar view showing the relation of the frame to the reed at the end of the drawing in operation, the backer, heddle release and presenting devices being shown in offset relation to the reed so as not to interfere with the threading of the last of the heddles in the frame.

Fig. 7 is a fragmentary elevational view of the heddle shifting mechanism with the parts in the relation occupied at the end of the drawing in operation, the initial position of the heddle frame being shown in broken lines.

Fig. 8 is a transverse sectional view taken approximately in the plane of line 8—8 of Fig. 2.

In the illustrative embodiment herein selected for purposes of illustration, I have shown a warp drawing machine comprising a main frame 10 in which is supported a harness consisting of a plurality of heddle frames 11, and a reed 12 (Fig. 3). The heddle frames are suspended by hooks 11a carried by blocks 11b having rollers 11c guided for movement along tracks 11d on the main frame 10; and the reed is stationarily supported rearwardly of the harness as viewed in Fig. 1, in parallel relation thereto. Thus the heddle frames are supported for endwise movement relative to the reed.

The heddles of each frame are released successively and presented to the drawing-in needle N (Fig. 3) by a heddle release key 13 and a turning or presenting worm 14, respectively mounted on shafts 15 and 16 on a carriage 17. The carriage is mounted upon the frame 10 for traveling movement under the control of a sensitive feed mechanism (not shown), in a manner well understood in the art.

Associated with each heddle frame is a backer 18 for maintaining the pack of unreleased heddles in compressed or compacted form. As shown, the free ends of the shafts 16 carrying the heddle presenting worms 14 are supported in bearing standards 19 on the carriage 17.

55 The relation of the heddle frames with respect

to the reed at the beginning of the drawing in operation is shown in Fig. 5. As the operation proceeds, the heddles are released successively by the release keys and presented to the drawing-in needle N (Fig. 3) by the turning worms 14.

In carrying out my invention, I provide means operating in timed relation to the movement of the carriage 17 for imparting a progressive shifting movement to all of the heddle frames of the harness in the direction of movement of the carriage, but at a reduced rate so as to shift the heddle frames from a normally aligned position with respect to the reed shown in Fig. 5 to a partially offset relation thereto as shown in Fig. 6. In the present instance, the means employed comprises an auxiliary carriage 20 in the form of a slide mounted on the main frame for movement in a direction parallel to the heddle frames and located at one end thereof (herein the left end as shown in Figs. 1 and 2); and for actuating the slide I provide gearing arranged for actuation by the carriage in its movement relative to the harness.

As herein shown, the carriage or slide 20 comprises a pair of rack bars 21 mounted in a frame member 22 of the machine in spaced parallel relation (Fig. 3) and having a pair of arms 23 connected by a cross bar 24. The arms 23 removably support a retaining rod 25 for insertion through the heddle frame as shown clearly in Figs. 2 and 4, thus providing a disengageable connection between the slide and the heddle frames. The upper ends of the brackets are additionally connected by a tie rod 26.

In the present instance, the cross bar 24 is positioned on the slide so as to provide a support for the lower heddle bar 27 of each heddle frame, the bar having an extension 28 projecting through the heddle frame so as to rest upon and be supported by the cross bar 24 independently of the heddles, thereby freeing the latter for free sliding movement relative to the frame. Also, it will be observed that the cross bar 24 bears against the adjacent end of each of the heddle frames so that movement imparted to the slide is transmitted to the heddle frames through the medium of the cross bar. The retaining rod 25 serves to connect the heddle frames with the slide so as to prevent movement of the frames relative to the slide due to frictional engagement between the backers and their respective frames and between the unreleased heddles and their supporting bars as the heddle frames move with the carriage in the drawing in operation.

The cross bar 24 of the slide is preferably mounted for adjustment into either of two positions with respect to the slide so as to accommodate heddle frames having heddles of different lengths. For this purpose the cross bar is provided with end flanges 29 slotted to receive clamping bolts 30 in the brackets 23 and the latter are provided with stop members 31 and 32 disposed respectively above and below the plates 29. By loosening the clamping bolts 30, the cross bar may be moved into position against either of the stops 31 or 32 according to the lengths of the heddles being operated upon.

The gearing connection between the main carriage 17 and the auxiliary carriage or slide 20 comprises in the present instance a pair of pinions 33 mounted on a shaft 34 and meshing with rack teeth 35 on the rack bars 21. The shaft 34 is suitably journaled in the main frame and has a rearward extension 34a (Fig. 3) carrying a pinion 36 meshing with an underlying rack bar 37

slidably supported in the machine frame 10, the extent of movement of this bar 37 relative to the frame being limited by guide studs 38 operating in slots 39 of the bar. As shown in Fig. 8, the studs 38 are secured to frame brackets 40 and are shouldered to clamp to the bracket an additional rack bar 41. The rack bar 41 is thus stationarily mounted in the machine frame and constitutes a portion of means operative in the movement of the main carriage 17 to transmit a proportional movement to the rack bar 37 connected with the slide 20. Such movement of the bar 37 is accomplished by two pinions 42 and 43 (Fig. 8) riveted together and respectively meshing with the stationary rack bar 41 and with the movable or actuating rack bar 37, the two pinions being mounted on a stub shaft 43a carried by a suitably elongated extension of the carriage 17. The pinion 43 is herein shown somewhat larger than the pinion 42, the latter having in the present instance twenty-seven teeth and the former twenty-five teeth.

It will be seen that as the carriage 17 moves to the right in Fig. 2, or to the left as shown in Fig. 25 4, rotational movement is imparted to the pinion 42 and thereby to the pinion 43 rigid therewith so as to cause the actuating rack bar 37 to move in the direction of movement of the carriage at a predetermined speed, the gearing being so proportioned as to cause the heddle frames to move in timed relation to the movement of the main carriage 17 but at a reduced rate such that at the end of the drawing in operation the heddle frames will occupy offset positions with respect to the reed as shown in Fig. 6. In this position, the backers 11, release keys 13 and heddle presenting worms 14 are disposed at the right-hand ends of the frames, thereby exposing the last remaining heddles in the frames for the threading operation.

At the end of the drawing in operation the operator may find it desirable to return the heddle frames to their initial positions in advance of the return of the main carriage, in order to facilitate removal of the harness from the machine and to permit manual replacement of any threads which may have been withdrawn from the dents of the reed due to the shifting of the frames relative to the reed. For this purpose, the actuating means 40 for the auxiliary carriage is constructed to provide a disengageable connection with the main carriage. In the present instance, the actuating rack bar 37 has its teeth 37a formed on a member 44 slidable with respect to the bar but normally held against movement relative thereto by means of a latch 45. The latter is pivoted on the bar 44 and normally engages with a shoulder 46 on the bar 37. The latch is formed with a finger-piece 47 so that it may be conveniently lifted out of engagement with the shoulder 46 thereby permitting relative movement between the teeth carrying member 44 and the bar 37 proper. Thus it will be seen that the operator may by grasping the tie rod 26 of the auxiliary carriage or slide 20 (having first lifted the latch 45) draw the slide to the left (Fig. 7) from the full line position therein indicated to that shown in broken lines. In this operation, the pinion 36 moves the rack member 44 along the bar 37 with the latch sliding along the upper edge of the bar. Thus the slide 20 is moved independently of the actuating rack 37 connected with the main carriage. When the latter is finally returned to its initial position, 75 the rack 37 will be moved thereby (to the right in

Fig. 7) until the latch 45 automatically reengages with its shoulder 46.

It is believed that the operation will be clear from the foregoing so that only a brief summary is necessary. Initially, the heddle frames occupy positions in transverse alignment with the reed 12, as shown in Fig. 5. As the drawing in operation proceeds, the main carriage 17 moves to the left (Fig. 4) or to the right in Fig. 2, causing pinions 42 and 43 to be rotated by reason of the stationary character of the rack bar 41. Rotation of the pinion 43 causes the actuating rack 37 to move in a direction opposite to that of the carriage but at a substantially reduced speed, and such motion is transmitted to the shaft 34 and through the medium of the pinion 33 to the rack bars 21, causing the slide 20 to shift the heddle frames progressively but at a reduced rate such that at the end of the drawing in operation the backers 18, release keys 13 and presenting worms 14 are disposed in offset relation to the reed, thereby permitting a full harness to be drawn in automatically. It will be observed that the progressive shifting movements imparted to the heddle frames causes the released heddles to assume a somewhat compacted form with the heddles evenly distributed along their respective frames. Upon the restoration of the frames to their initial positions, the heddles may be shifted along their respective supporting bars by the operator drawing upon the inserted threads.

I claim as my invention:

1. In a warp drawing machine having a stationary machine frame with reed and harness supporting means thereon and a carriage mounted for movement along the frame and having means operative upon the harness to release and present successive heddles to the operation of a drawing-in needle, said harness supporting means being adapted to support a plurality of heddle frames parallel to the reed and each slidably supporting a pack of heddles with a backer therefor; means actuated by the carriage and directly connected with the heddle frames to shift the same endwise parallel to the reed, the last mentioned means operating in timed relation to the carriage but at a reduced speed.

2. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness supporting means being adapted to support a plurality of heddle frames in parallel relation to each other and to the reed and each slidably supporting a pack of heddles with a backer therefor; means directly connected with the heddle frames and actuated by the carriage in timed relation to the release and presentation of the heddles to the drawing-in needle to shift the heddle frames progressively relative to the reed whereby to carry their respective backers out of transverse alignment with the reed at the end of the drawing-in operation.

3. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each

other and to the reed and each supporting a pack of heddles with a backer therefor; heddle frame shifting mechanism operative in the movement of the carriage incident to such release and presentation of the heddles to impart a shifting movement to the heddle frames relative to the reed and in the direction of movement of the carriage but at a reduced rate, said mechanism including an auxiliary carriage mounted in the machine frame for movement in a direction parallel to the main carriage and operatively associated with the heddle frames of the harness to move the same relative to the reed.

4. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; heddle frame shifting mechanism operative in the movement of the carriage incident to such release and presentation of the heddles to impart a shifting movement to the heddle frames relative to the reed and in the direction of movement of the carriage but at a reduced rate, said mechanism including an auxiliary carriage mounted in the machine frame for movement in a direction parallel to the main carriage and operatively associated with the heddle frames of the harness to move the same relative to the reed, and means actuated by said main carriage for imparting a gradual shifting movement to the auxiliary carriage.

5. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; a heddle frame shifting mechanism comprising an auxiliary carriage mounted in the machine frame for movement in a direction parallel to the main carriage and operatively associated with the heddle frames of the harness to move the same relative to the reed, said auxiliary carriage having a gearing connection with the main carriage operative to move the auxiliary carriage in the direction of movement of the main carriage but at a reduced rate.

6. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; a heddle frame shifting mechanism comprising an auxiliary carriage mounted in the machine frame for movement in a direction parallel to the main carriage and operatively associated with the heddle frames of the harness to move the same

relative to the reed, said auxiliary carriage having a gearing connection with the main carriage comprising a stationary rack, a movable rack operatively connected with the auxiliary carriage, and a pair of pinions rotatably mounted on the main carriage and respectively engaging said racks, said pinions being connected for rotation in unison.

7. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; a heddle frame shifting mechanism comprising an auxiliary carriage mounted in the machine frame for movement in a direction parallel to the main carriage and operatively associated with the heddle frames of the harness to move the same relative to the reed, said auxiliary carriage having a gearing connection with the main carriage comprising a rack bar rigid with the auxiliary carriage, a pinion meshing with said rack bar and mounted for rotation on a fixed axis, a movable rack bar, a pinion meshing with said movable rack bar and connected with the first mentioned pinion to actuate the same, and means operable by the main carriage for actuating said movable rack bar.

8. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; means operative in the movement of the carriage incident to release and presentation of the heddles to impart a shifting movement to the heddle frames relative to the reed comprising an actuating member movable with the main carriage and operatively connected with the heddle frames, said member having a disengageable connection with the main carriage to permit of movement of the heddle frames independently of said actuating member.

9. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; means operative in the movement of the carriage incident to such release and presentation of the heddles to impart a shifting movement to the heddle frames relative to the reed comprising an auxiliary carriage operatively connected with the heddle frames and having a driving connection with the main carriage disengageable to permit movement of the auxiliary carriage independently of the main carriage and automatically re-

engageable in the return movement of the carriage.

10. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; a heddle frame shifting mechanism comprising an auxiliary carriage mounted in the machine frame for movement in a direction parallel to the main carriage and operatively associated with the heddle frames of the harness to move the same relative to the reed, said auxiliary carriage having a gearing connection with the main carriage comprising a shaft having a driving connection with the auxiliary carriage, a pinion on said shaft and an actuating rack bar operatively connected with the main carriage and having a toothed member meshing with said pinion, said member having a disengageable connection with the bar to permit of movement of the toothed member independently of the bar.

11. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; means operative in the movement of the carriage incident to such release and presentation of the heddles to impart a shifting movement to the heddle frames relative to the reed comprising an auxiliary carriage having an operative connection with the main carriage for movement thereby including a bar connected with the main carriage and having a slide thereon and a latch normally holding the slide against movement relative to the bar, said slide having rack teeth thereon, and a motion transmitting connection between said slide and said auxiliary carriage including a pinion meshing with the teeth of the slide.

12. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; means operative in the movement of the carriage incident to such release and presentation of the heddles to impart a shifting movement to the heddle frames relative to the reed comprising an auxiliary carriage slidably mounted for movement in the main frame of the machine, and a member mounted on said auxiliary carriage and providing a support for the harness.

13. In a warp drawing machine having a stationary machine frame, a drawing-in needle, reed and harness supporting means carried by the frame and a carriage mounted for movement

along the frame and having means operative upon the harness to release and present successive heddles to the operation of said drawing-in needle, said harness including a plurality of heddle frames supported in parallel relation to each other and to the reed and each including a heddle supporting bar; means operative in the movement of the carriage incident to such release and presentation of the heddles to impart a shifting movement to the heddle frames relative to the reed comprising an auxiliary carriage operatively connected with the main carriage and providing a support for said heddle supporting bar.

14. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each having a heddle supporting bar; means operative in the movement of the carriage incident to such release and presentation of the heddles to impart a shifting movement to the heddle frames relative to the reed comprising an auxiliary carriage having a member engageable with the heddle frames to move them and a second member insertable through the heddle frames to connect the frames to the auxiliary carriage, the first of said members providing a support for said heddle bars and being adjustable vertically relative to the auxiliary carriage.

15. In a warp drawing machine having a stationary machine frame, a drawing-in needle, reed and harness supporting means carried by the frame and a carriage mounted for movement along the frame and having means operative upon the harness to release and present successive heddles to the operation of said drawing-in

needle, said harness including a plurality of heddle frames supported in parallel relation to each other and to the reed and each supporting a pack of heddles with a backer therefor; means operative in the movement of the carriage incident to such release and presentation of the heddles to impart a shifting movement to the heddle frames relative to the reed comprising an auxiliary carriage having a member engageable with the heddle frames to move them and a second member removably supported and insertable through the heddle frames to connect the frames to the auxiliary carriage.

16. In a warp drawing machine having a stationary machine frame, a drawing-in needle, reed and harness supporting means carried by the frame and a carriage mounted for movement along the frame and having means operative upon the harness to release and present successive heddles to the operation of said drawing-in needle, said harness including a plurality of heddle frames supported in parallel relation to each other and to the reed and each supporting a pack of heddles with a backer therefor; means operative in the movement of the carriage incident to such release and presentation of the heddles to impart a shifting movement to the heddle frames relative to the reed comprising an auxiliary carriage having a disengageable connection with the heddle frames.
